CLAIM

The ornamental design for a planter, as shown and described.

DESCRIPTION

FIG. 1 is a perspective view of a planter showing my new design;

FIG. 2 is a left side view thereof, the right side view, front and back views of the claimed portion of the design being identical to the left side view;

FIG. 3 is a top plan view thereof; and,

FIG. 4 is a cross-sectional view thereof taken on line 4-4 in FIG. 3.

The broken lines in the drawings are included to show features that form no part of the claimed design.
